UNITED STATES PATENT OFFICE.

JACOB KAUFMANN, OF PHILADELPHIA, PENNSYLVANIA, ASSIGNOR TO STEEL HEDDLE MANUFACTURING COMPANY, OF PHILADELPHIA, PENNSYLVANIA, A CORPORATION OF PENNSYLVANIA.

HEDDLE-FRAME.

1,090,859.

Specification of Letters Patent. Patented Mar. 24, 1914.

Application filed October 19, 1912. Serial No. 726,618.

To all whom it may concern:

Be it known that I, JACOB KAUFMANN, a citizen of the United States, residing at Philadelphia, in the county of Philadelphia and State of Pennsylvania, have invented 5 certain new and useful Improvements in Heddle-Frames, of which the following is a specification.

My invention relates to heddle frames for 10 looms, and it has particular relation to means for supporting the heddle bars intermediate their ends.

The principal object of my invention is to 15 provide improved means for supporting the heddle bars intermediate their ends which will securely support said bars against undesirable motion, but which however will permit the bars to be easily mounted in and dismounted from the frame when desired.

Heretofore various devices have been employed to support the heddle bars intermediate their ends to prevent their displacement or distortion while in use, these devices 20 commonly consisting of hooks of various shapes which were secured to the frame and were usually open at the end toward the heddle frame rail to permit the insertion of the heddle bar. On account of one end of these 25 hooks being open, the heddle bar was permitted considerable movement during the reciprocation of the heddle frame in the loom, which movement would be suddenly arrested on the reversal of the motion of the heddle frame by the bar striking against the 30 closed end of the hook, thereby causing the hooks to quickly wear through and permitting the bars to become displaced. The destruction of a large part of the structure by 35 fouling of adjoining harness was frequently 40 caused in this manner.

My present invention contemplates a form 45 of supporting means which, permitting the ready insertion of the heddle bar, yet will maintain the same against undue movement 5 and thereby overcome the objections above mentioned.

The nature and characteristic features of 50 my invention will be more readily understood from the following description, taken 0 in connection with the accompanying drawings forming part hereof, in which—

Figure 1 is a front elevation of a heddle frame, with a supporting device embodying the main features of my present invention

shown mounted therein; Fig. 2 is an enlarged side elevation of the supporting device detached, but with a portion of the heddle bar shown in operative relation thereto; Fig. 3 is a similar view, but taken transversely to Fig. 2; Fig. 4 is a horizontal section, still further enlarged, of the supporting device, the section being taken on the line 4—4 of Fig. 3; Fig. 5 is a fragmentary perspective view of the supporting member, a portion of the heddle frame in which it is 55 mounted, and a portion of the heddle bar in its normal mounted position; and Fig. 6 is 60 a view similar to Fig. 5, but with the parts in the positions assumed during the insertion of the heddle bar in the supporting 65 member.

Referring to the drawings, the heddle frame there shown consists of the top and bottom rails 7, usually made of wood, and connected at their ends by means of the end 75 straps 8. Extending from end to end of the heddle frame, and arranged near the top and bottom rails in the usual manner, are the heddle bars 9, upon which the heddles 10 are mounted.

The supporting device forming the novel 80 portion of my present invention comprises a screw-threaded shank 11 which is adapted to be screwed into the top and bottom rails 7 at the desired locations. The rails 7 are 85 usually made of wood, although in the event of their being made of metal, it will be readily understood that the shank 11 may be modified accordingly, the essential being that this shank may be capable of forced rotation with respect to the rails 7, but against 90 the frictional resistance by which they are held in the desired positions. Secured to the threaded shank 11 in any suitable manner are two parallel plates 12 which, as 95 shown, may be secured by means of a rivet 13 to the screw-threaded shank 11, and are prevented from rotation about said rivet by making their ends bifurcated and having the bifurcated portion bent over as at 14 to 100 engage the shank 11, as clearly shown in Figs. 2, 5 and 6 of the drawings. If desired the plates 12 may be welded to or formed integral with the shank 11. The plates 12 are separated from each other a 105 distance at least equal to the thickness of the heddle bars 9, and each of said plates is provided with a recess 15 which extends

to the edge of one plate 12 at one side and to the edge of the other plate 12 on the opposite side as shown in Figs. 4, 5 and 6 of the drawings. The recess 15 is of a width 5 corresponding to the width of the heddle bar 9 which is supported therein in the assembled condition of the structure as shown in Figs. 1 to 5 of the drawings.

The heddle bar 9 is inserted in the supporting member by first turning said member until the plates 12 lie parallel to the longitudinal extension of the frame rails 7 as shown in Fig. 6 of the drawings, whereupon the heddle bar 9 may be inserted between 15 said plates until it occupies a position opposite the recesses 15, after which the supporting member is turned 90°, against the frictional resistance offered by the rail 7 in which it is mounted, until it occupies the position shown in Fig. 5, whereupon the solid portion of each plate 12 opposite its recess will serve to confine the bar 9 against undue sidewise movement. It should be understood that the heddle supporting bars 9 are 25 usually rectangular in cross section and are limited in their transverse dimensions on account of the relatively small permissible size of the mortised ends of the heddles which are mounted thereon. On account of 30 this limited dimension, where these bars are of great length, they are likely to be distorted sidewise during the reciprocation of the heddle frames in the loom.

It will be seen that there is thus provided 35 an improved form of supporting device for preventing the distortion or displacement of the heddle bars intermediate their ends, and which will maintain said bars against undue movement tending to the destruction of the 40 structure as well as reducing the wear on the supporting device, but which however will permit the heddle bars to be easily mounted in the frame with the heddles in place thereon, and which may be inexpensively constructed while extremely efficient in operation.

Having thus described the nature and characteristic features of my invention what I claim as new and desire to secure by Letters Patent is:

1. In a heddle frame, the means for supporting the heddle bars intermediate their ends comprising a device having two extending plates separated to permit the heddle 55 bar to be inserted therebetween, and each of said plates having a recess to receive the bar and support the same against undue movement, the device being rotatably mounted in the frame to cause the space between

said plates to extend either longitudinally 60 or transversely for the purpose set forth.

2. In a heddle frame, the means for supporting the heddle bars intermediate their ends comprising a device having two extending plates separated to permit the heddle 65 bar to be inserted therebetween, and each of said plates having a recess to receive the bar and support the same against undue movement, said recesses extending to the side edges of their respective plates, the 70 device being rotatably mounted in the frame to cause the space between said plates to extend either longitudinally or transversely for the purpose set forth.

3. In a heddle frame, the means for supporting the heddle bars intermediate their ends comprising a device having two extending plates separated to permit the heddle bar to be inserted therebetween, and each of said plates having a recess to receive the bar and support the same against undue movement, the recess in one plate extending to one side edge and the recess in the other plate extending to the other side edge thereof, the device being rotatably 85 mounted in the frame to cause the space between said plates to extend either longitudinally or transversely for the purpose set forth.

4. In a heddle frame, the means for supporting the heddle bars intermediate their ends comprising a device having a shank in rotatable frictional engagement with the heddle frame rail and having two plates extending from said shank, each of said plates 95 having a recess to receive and support the heddle bar, said recesses being oppositely disposed.

5. In a heddle frame, the means for supporting the heddle bar intermediate its ends 100 comprising a device having a shank in threaded engagement with the heddle frame rail, and having two plates extending from said shank and separated to permit the insertion of the heddle bar therebetween, and 105 each of said plates having a recess to receive the bar and support the same against undue movement, the recess in one plate extending to one side edge and the recess in the other plate extending to the opposite side 110 edge thereof.

In testimony whereof, I have hereunto signed my name in the presence of two witnesses.

JACOB KAUFMANN.
